UNITED STATES PATENT OFFICE.

T. TRASK WOODWARD, OF PANA, ILLINOIS, ASSIGNOR TO DUANE T. DAVIS,
OF SAME PLACE.

VAPOR-BURNER.

SPECIFICATION forming part of Letters Patent No. 270,194, dated January 2, 1883.

Application filed October 13, 1882. (No model.)

To all whom it may concern:

Be it known that I, T. TRASK WOODWARD, a citizen of the United States, residing at Pana, in the county of Christian and State of Illinois, have invented a new and useful Improvement in Vapor-Burners, of which the following is a specification.

My invention relates to new and useful improvements in vapor-burners; and it consists in certain novel details of construction and arrangement, as will be hereinafter more fully described, reference being had to the accompanying drawings, in which—

Figure 1 is a side elevation, partially in section, showing the interior construction of its improved parts. Fig. 2 is a top plan of the lower or generator portion of the burner. Fig. 3 is top plan of the upper removable cap, and represents the location of the series of perforations.

Similar letters refer to similar parts throughout the several views.

A represents the base or generating portion of the burner, provided with a central tube, a'.

B is the valve, which is screwed into the bottom of the part A, and may be either a needle or common screw valve, such as is now in use.

C is a gas-chamber, which is formed within the cup portion of the base and forms a part of the central tube, and also a part of the outer rim of the cup. This gas-chamber rises above the inlet of the gas from the generator D, and acts upon the same principle as the air-chamber of a pump to steady the flow, and also as a secondary or superheating chamber. Communication from the generator D to the gas-chamber C is had through a very small channel, as shown at C'. It is found that by this construction of the lower base of the burner all valves, filters, and regulators are dispensed with, as the gas contained within the chamber C has sufficient force to control the flow of fluid, as said chamber rises above the inlet-orifice of the fluid-conduct.

E is a removable bell-shaped cap having a central hole, which forms a continuation of the central tube, a', of the base.

F is a terrace-shaped cap, and is provided

with four rows or series of perforations, as indicated by letters c c' c'' c''''. The holes in the lower series, c, are square notches cut into the lower edge of the cap, and are of a much larger size than the holes in the other series. The holes c' are located near the edge of the first terrace, and are drilled so as to emit a vertical flame, while the holes in the series c'' are drilled directly into the side of the dome at the point of junction with the terrace, and they are located intermediately between the series c', so that the flame from each series will not intermingle with each other. At or near the top of the dome of this cap is a series of perforations, c''', also drilled in horizontally. The direction of the flame is indicated by curved lines in Fig. 1.

It will be obvious that the inner bell-shaped cap, E, forms a gas-chamber, or, rather, a combustion-chamber, surrounding the vertical tube a', also enveloping the inner or superheating generator, C. It forms a continuation of the central tube, a', and adds materially to its force.

While this burner may be used successfully without the inner bell-shaped cap, E, caps of various forms, having more or less perforations, may be used, as has been found by actual experiment. With this base or double generator, constructed as shown, the most perfect and satisfactory results are not attained entirely by the specific formation of the upper cap as heretofore held; but the success lies mainly in the construction of the lower bases of the burner and generators, as herein represented.

As to the inner bell-shaped cap, it is admitted that this adds materially to the power of the generator, and by adding to the power of the generator the force of the flame is proportionately increased, as it confines the flames within the lower or combustion chamber of the base of the burner, enveloping the superheating generating-chamber, and producing a most intense heat, which acts upon the generator. There are two holes, e e—one on each side of the generator—through the side wall of the lower chamber of the burner, which cast a flame against the alternate sides of said generator, as shown in Fig. 2.

It has been found from actual tests that the

within-shown terrace-shaped cap, in connection with the inner bell-shaped cap, gives the most perfect combustion and the most intense heat, rendering the flame perfectly odorless by its use in combination with the lower base and its generators.

Having thus described my invention, what I believe to be new, and desire to secure by Letters Patent, is—

- 10 1. A vapor-burner having the cup-shaped base A, in combination with the bell-shaped cap E, and the terrace-shaped cap F, provided with the separate series of perforations $c c' c'' c'''$, substantially as shown and described.
- 15 2. A vapor-burner having the cup-shaped base A, provided with the generating-chamber D and heating-jets $e e'$, and the secondary or gas-superheating chamber C, located above the primary generator D, and connected therewith

by a suitable small tube, C', in combination 20 with the terrace-shaped cap F, provided with the series of perforations $c c' c'' c'''$, and depending suitably-valved jet-tube, substantially as shown and described.

3. A vapor-burner having the cup-shaped 25 base A, provided with primary generating-chamber D and superheating or secondary chamber C, and suitable connecting-tube leading upward thereinto from the said chamber D, in combination with the removable cap E, 30 the terrace-shaped cap F, provided with the series of perforations $c c' c'' c'''$, and a depending suitably-valved jet-tube, substantially as shown and described.

T. TRASK WOODWARD.
